UNITED STATES PATENT OFFICE.

LINWOOD M. WHITEHEAD, OF NORFOLK, VIRGINIA.

TALLYING-MACHINE.

1,391,086.

Specification of Letters Patent. Patented Sept. 20, 1921.

Application filed August 11, 1919. Serial No. 316,840.

To all whom it may concern:

Be it known that I, LINWOOD M. WHITEHEAD, a citizen of the United States, and a resident of Norfolk, Norfolk county, and State of Virginia, have invented certain new and useful Improvements in Tallying-Machines, of which the following is declared to be a full, clear, and exact description.

10 This invention relates to tallying machines and its principal objects are to provide a highly efficient device for automatically registering the number of truck loads transported from one place to another. It is well known that a record or tally is kept of the number of truck loads, loaded on or unloaded from freight cars, vessels or freight houses, warehouses or other transport mediums or storage places, and the 15 usual practice is to employ a workman to perform the task of keeping record or tally of the number of truck loads. Mechanical devices have also been used for this purpose and it is the principal object of this invention to increase the efficiency of machines of this type, to provide improved means for preventing accidental operation of the register mechanism; to prevent tampering there- 20 of, to indicate the approach of the last of the predetermined truckloads, to place a barrier in the path way of the trucks when the predetermined loaded number have been 25 counted and to otherwise improve upon devices of this class.

30 The invention consists in the several novel features hereinafter fully set forth and claimed.

The invention is clearly illustrated in the accompanying drawings, in which:—

40 Figure 1 is a perspective view of a tallying machine embodying a simple form of the present invention; Fig. 2 is a vertical cross section taken through the platform of the device; Fig. 3 is a rear elevation with the back wall or cover removed; Fig. 4 is a detail side elevation of the barrier retainer, the case being shown in vertical section taken on the line 4—4 of Fig. 3; Fig. 5 is a side elevation of the parts seen in Fig. 4, but showing the parts in released position; Fig. 6 is a rear elevation of the register actuating mechanism seen in Fig. 3 but showing the parts in effective position for tallying; Fig. 7 is an edge view of said mechanism looking in the direction of the

arrow 7 in Fig. 6; Fig. 8 is a detail vertical cross section taken on line 8—8 in Fig. 6; Fig. 9 is face view of one of the dials and hands; Fig. 10 is a rear elevation of the register mechanism and barrier release 60 mechanism; Fig. 11 is a fragmental rear elevation of certain members of the barrier release mechanism in released position; Fig. 12 is a central vertical longitudinal section taken on line 12—12 of Fig. 10, and Fig. 65 Fig. 13 is a fragmental vertical section taken on line 13—13 of Fig. 2.

Referring to said drawings, which illustrate a simple embodiment of the present invention, it will be seen to consist generally 70 of a platform 15 (see Figs. 1, 2 and 13) which is placed in the path of travel of the trucks, and on which they must pass to and from the place from whence the loads are removed. Inclined approaches 16, 17 are removably secured to the platform and preferably are provided with guide bars 18 to direct the wheels of the trucks to the operating levers. Other guides 19, 20 are provided on the platform which extend between 75 the bars 18, and a board 21 located above the levers, extends between the inclined approaches 16, 17, upon which board the trucker steps when he crosses the platform. The truck wheels pass through the passage 80 ways *a*, *b*, left between the bar 19 and board 21 and between said board and bar 20. An upright case on compartment 22 is secured to and extends up from one end of the platform and contains the mechanism for actuating the various tripping mechanism, 85 register mechanism, barrier actuating mechanism, and alarm, as will be more fully set forth hereinafter. Conveniently, handles 23 are provided at one end of the platform for 90 moving the device about, and rollers 24 are provided at the other end upon which rollers the device may be wheeled about.

The register actuating mechanism.

100

Pivottally supported in the platform 15, are four primary or platform levers 25, 26, 27 and 28 (see Figs. 1, 2, 3 and 13), the upper edges of which are normally located above the bottom of the passage ways *a*, *b*, and said primary levers are adapted to be depressed, in succession, by the truck wheels passing over the platform in either direction, but the mechanism is so constructed 105 and arranged that operation of the register 110

mechanism is only effected by the depression of the primary levers in succession by the truck wheels passing over the platform in the proper direction. The arrows α , in Figs. 1, 2 and 3, indicate the direction of travel of loaded trucks, and when trucks are moved across the platform in said direction the register will be actuated each time a truck passes the platform, movement of the 10 trucks across the platform in the opposite direction having no effect on the registering mechanism. For convenience the lever 25 will be called the release lever; the lever 26 will be called the setting lever; the lever 27 will be called the register actuating lever, and the lever 28 will be called the second release lever.

Pivottally supported in the lower end of the case 22 and extending transversely there- 20 of are four secondary levers 25^a 26^a 27^a and 28^a which are connected, respectively, to the primary levers by links 25^b, 26^b, 27^b and 28^b. Springs 25^c, 26^c, 27^c and 28^c secured to the secondary levers and to some stationary part 25 of the framework act to return the levers to normal or inoperative, raised position.

The release lever 25 is connected to a detent 29 (see Fig. 3) by the link 25^b, secondary lever 25^a, a link or rod 25^d, a bell crank lever 30 and a link 31 which is secured to the detent 29 and has a lost motion connection with one arm of the bell crank lever 30. The detent 29 and bell crank lever 30 are pivottally mounted upon one wall or frame 35 member 32 of a gear case which is fastened in place in the compartment 22, and are spring actuated by springs 29^a, 30^a secured to the detent 29 and bell crank lever 30 respectively. The spring 30^a acts to return lever 40 30 to normal, inoperative position (see Fig. 3) after lever 25 has been released, and spring 29^a acts to swing the detent 29 over the setting arm 33 whenever the latter is 45 swung down. Depression of the release lever 25 swings the bell crank lever in the direction of the arrow thereon in Fig. 3, and operates to release the setting arm 33, in case it has been set. If it has not been set, the bell crank lever 30 swings idly on its ful- 50 crum when the release lever is depressed.

The setting lever 26 is connected to the setting arm 33 by the link 26^b, secondary lever 26^a and a link 26^d. The setting arm 33 is pivottally supported on the gear case mem- 55 ber 32 and one end 34 thereof bears against a register actuating link member 35 and operates to swing it in the direction of the arrow thereon in Fig. 3 whenever the setting lever is depressed, thereby placing said link 60 member 35 in position for operative engagement with its companion link member 36. The link members 35, 36 have co-acting hook-like portions which, when the setting arm has been swung down, and the link 65 member 35 has been moved into the posi-

tion seen in Fig. 6, are in position for co-operative engagement when the link member 36 is moved downward. It is to be observed that whenever the setting arm is swung down, the detent 29 is instantly swung over 70 the end 34 of the setting arm (see Fig. 6) by the spring 29^a thereby temporarily holding said setting arm in operative position with the link members 35, 36 in operative relation to each other. Furthermore, that unless the setting arm is held in such operative position the link member 36 may be moved up and down without effecting its companion link member 35.

The register actuating lever 27 is connected to the link member 36 by the link 27^b, secondary lever 27^a and a link 37, and the link member 36 is guided to move in a vertical direction in guide brackets 38, 39 secured to the gear case member 32. A stop 85 member or projection 40 limits the upward movement of the link member 36. Each time the register actuating lever 27 is depressed, the link member 36 is moved downward, but unless the link member 35 has 90 been moved into operative position (see Fig. 6) the link member 36 will be moved idly. The upper end of the link member 35 is guided in a guide bracket 41 pivottally mounted on the gear case member 32, and 95 it is connected to the register actuating arm 42 by a link 43. A spring 42^a connected to link 42 acts to swing it upward and a stop 42^b limits its upward movement. A release lever 44 pivottally mounted on the gear case 100 member 32 has an end which is pressed against the link member 35 by a spring 45 secured to the other arm of the release lever 44 and to the gear case member 32. Pressure is exerted by the spring actuated release lever 44 in a direction tending to disconnect the hooks of the link members 35, 36 from each other, to thereby break the connection between said link members, so 105 that after the setting arm 33 has been released from the detent 29 and swung back to normal position (see Fig. 3) the release lever 44 swings said link member 35 out of operative relationship with the link member 36. The link member 35 has a shoulder 110 46 thereon which is arranged to engage the detent 29 while the link member 35 is being moved downward, to thereby disengage the detent 29 from the setting arm 33, permitting the latter to be retracted from the link 115 member 35.

The second release lever 28 is connected to the bell crank lever 30 by the link 28^b, secondary lever 28^a a link 28^d, which extends between secondary levers 28^a and 25^a and the link 25^d, and the function of said lever 28 is to release the detent 29 from the setting arm 33 in case it is accidentally engaged with the setting arm after the register actuating lever has been depressed by 120 130

a truck passing over the platform in the direction to operate the register.

The register mechanism.

5 Any suitable form of registering, recording or indicating means may be employed for indicating the number of times the register has been operated. In the form illustrated, dials and hands or pointers are employed. Means are provided, whereby certain indicating hands may be set at the numeral on the dial, corresponding with the predetermined number of truck loads that are to be counted, and means are provided whereby an alarm is sounded shortly before the total number have been counted, and a barrier is moved into the path over the platform when the total number of truck loads have passed over the platform. 10 In the simple form of register illustrated two dials 48, 49 (see Fig. 1) are employed, which are secured on the front wall 50 of the case or compartment 22. On each dial are two annular rows of numerals (see Fig. 25 9) the outer row indicating units and the inner row indicating hundreds. Hands or pointers 51, 52, 51^a, 52^a operated by the register mechanism are employed to indicate on the dials the number of loads passing over the platform. The hands 51, 52 are driven by simple gearing, operated by the register actuating arm 42, which, as shown, comprises a ratchet wheel 53 fast on a shaft 54 journaled in the members 32, 35 55 of the gear case. A pawl 56 (see Figs. 3, 6) carried by the register actuating arm 42 and held in contact with the teeth of the ratchet wheel 53 by a spring, advances said ratchet wheel one tooth or one step each 40 time the arm 42 is swung down from the position shown in Fig. 6 and back to said position. A stop 56^a is located on the gear case member 32 in position to positively arrest movement of the pawl 56 and ratchet wheel 53, when the lever 42 strikes the stop 42^b, and thereby prevent the ratchet wheel 53 from moving more than one step at a time. A spring actuated detent 57 on the gear case plate 32 engages with the teeth 45 of the ratchet wheel and prevents retrograde movement thereof. 50 The shaft 54 has a pinion 58 secured thereon, which meshes with a gear wheel 59 fast on the shaft 60 which carries the hand 51. The hand 52 is mounted on a hollow shaft 61 (see Fig. 12) which surrounds the shaft 60 and is driven from the gear wheel 59 by a train of gears 62, 63 and 64, the gear wheel 64 being fast on the hollow shaft 61. Conveniently the outer row of numerals on the dial may run numerically from "1" to "100" and the gearing for the hand 51 is consequently made to impart one complete revolution to the gear wheel 59 and hand 51 when the register actuation 55 arm 42 has been operated one hundred times. The gearing for the hand 52 is arranged to impart one complete revolution to the gear wheel 64 and hand 52 each time the hand 51 has made ten complete revolutions. In 70 other words, the hand 52 is moved one-tenth of a revolution each time the hand 51 makes one complete revolution.

The gearing for the hands 51^a, 52^a of the dial 49 may be identical with that described for the hands of the dial 48, and comprises the pinion 58 and gear wheel 59^a fast on the shaft 60^a for the hand 51^a, and the pinions 62^a, 63^a and gear wheel 64^a for the hand 52^a, the gear wheel 64^a being fast 80 on the hollow shaft 61^a for the hand 52^a. The shafts for the gearing are journaled in the gear case in the ordinary manner, but the shaft 54 is slidably movable therein and it has a knob 65 on its outer end by 85 which it may be pressed inward to demesh the pinion 58 from the gear wheels 59, 59^a which is done when setting the hands 51, 52. A coiled compression spring 66 bearing against the pinion 58 normally holds the 90 pinion 58 in mesh with the gear wheels 59, 59^a. Detents 67, 67^a frictionally engage the teeth of the gear wheels 59, 59^a to prevent accidental movement thereof.

The barrier and alarms.

Pivotedly mounted on the case or compartment 22 is the barrier 68 (see Figs. 1, and 4) which is in the form of a rod or bar, normally held in inoperative position 100 along side the case by a hook or latch 69 and shoulder 70. A spring 68^a operates to swing the barrier from inoperative position to a position barring passage across the platform. Barrier releasing mechanism, 105 operated from the gear wheel 64 is provided for releasing the barrier from the hook or latch 69 immediately after the last loaded truck of the predetermined number has depressed the register actuating lever 110 and registered the total predetermined number. In the simple form of barrier releasing mechanism shown, a vertically reciprocating rod 71 is employed for tripping the hook or latch from its locked position. 115 Said rod 71 is guided in brackets 72 secured to the wall 50 of the case 22 and is normally held in raised position by a pawl or detent 73, which engages with the underside of a shoulder 74 on the rod 71. A spring 75 secured to the rod and case acts to move the rod in a downward direction when it is released from the detent 73. The detent 73 is yieldingly held in engagement with the rod and its shoulder 74 by a spring 76.

Extending from the gear wheel 64 is a pin 77 (see Figs. 10 and 11) and normally lying in the path of travel of said pin is one end of a trigger member 78, here shown in the form of a rod or bar, the other end of 130

which normally stands directly in front of 5
detent 73. Said trigger is fulcrumed upon
a pin 79 and also has a sliding connection
with said pin which extends through a slot
80 in the trigger. A coiled spring 81 con-
necting the trigger with the gear case acts
to hold the trigger in position with one end
in the path of travel of the pin 77 and the
other directly in front of the trigger 73.
10 A stop or shoulder 82 on the case limits the
upward pull of the spring 81 on the trigger.
The trigger is connected to the rod 71 by
a link 83 which acts to swing the end of the
trigger (which contacts with the pin 77)
15 upward out of its way whenever the rod 71
is lowered to release the barrier.
The lower end of the rod 71 is connected
to a latch operating hook 84 by a bolt 85,
and a yielding connection between the two
20 is provided by a spring 86 which is inter-
posed between the rod 71 and hook 84. Said
hook is pivotally supported on the inside
of the front wall 50 of the case 22 and is
connected to the latch 69 by a link 88, which
25 is attached to the latch below its pivot 89.
The latch projects out through a slot in the
wall 50 and its upper edge is made concave
to receive and hold the barrier in place. The
hooked end of the hook 84 normally over-
30 hangs and engages the top edge of the latch
and cooperates with the link to hold the
latch in raised position holding the barrier.
When the rod 71 is moved down the hook
84 is swung out of engagement with the
35 latch (see Fig. 5) the latter positively swung
down to release the barrier, which is there-
upon swung out across the platform by the
spring 68^a. To reset the barrier it is swung
back into the hollow of the latch and the
40 latch raised, thereby, swinging forward the
hook 84 into engagement with the latch and
raising the rod 71 into locked engagement
with the detent 73.

To signal the truckers, and thus warn
45 them and the attendant that nearly all of
the predetermined number of truck loads
have passed through the tallying device,
means are provided for ringing a bell from
the time that nearly all of the loads have
50 passed until the last one has passed. Said
means may comprise an electric bell 90,
wired to a battery 91, and a switch, com-
prising the detent 73 and a spring pressed
contact member 92, which are interposed
55 in the bell circuit. A setscrew 93 threaded
with contact member 92 and bearing against
a stop 92^a furnishes means of adjustment
for the contact member 92 whereby the exact
timing of making the contact between
60 the contact members occurs. The parts are
so arranged that before the trigger 78 com-
pletely disengages the detent 73 from the
rod 71 it first forces the detent 73 into contact
with the contact member 92 thereby closing
65 the circuit and causing the bell 90 to ring.

The bell continues to ring until the last load
operates the register, at which time the pin
77 has moved the trigger 78 far enough to
disengage the detent 73 from the rod 71,
thereby releasing the rod 71, which is pulled
70 down by spring 75, and disengaging the
trigger 78 from the detent 73 which is there-
upon moved out of contact with the contact
piece 92 by spring 76 (see Fig. 11). If de-
sired, a gong 95 may be employed for sig-
75 naling each time that the register is actuated,
the arm of said gong being connected
to the register actuating arm 42 by a link 96.

In the operation of the tallying machine,
the lower indicating means indicates the to-
80 tal number of truck loads that pass over the
platform, and ordinarily the hands thereof
are not set back after a predetermined num-
ber of truck loads have been counted but
said indicator shows the total promiscuous
85 loads.

To set the upper indicator, to thereby op-
erate the barrier and sound the alarm when
a predetermined number of truck loads have
been tallied the knob 65 is pushed back,
90 thereby demeshing the pinion 58 from the
gears 59, 59^a, and the hands 51, 52 there-
upon set opposite the numerals indicating,
in units and hundreds, the predetermined
95 number of truck loads which are to be ac-
counted for, the knob is released and the
machine is ready for operation. The load-
ed trucks are pushed across the platform in
the direction of the arrows, α , in Figs. 1, 2
and 3 and the empty trucks returned over
100 the platform in the opposite direction, the
truck wheels depressing the primary levers
in succession in passing over the platform.

Loaded trucks first depress the release lever
25 thereby releasing the detent 29 from
105 the setting arm 33 in case it had not been re-
leased therefrom, as for instance if the set-
ting lever 26 had previously been stepped
upon or otherwise had been accidentally de-
pressed. After passing said release lever 25,
110 the truck wheels depress the setting lever
26 thereby swinging downward the setting
arm 33 and setting the upper link member 35
in position for operative connection with the
lower link member 36. Simultaneously, the
115 spring 29^a swings the detent 29 over the set-
ting arm 33 holding it in locked, operative
position. The wheels next depress the reg-
ister actuating lever 27 thereby pulling down
the register actuating arm 42 through the
120 instrumentality of the connected link mem-
bers 35, 36 and associated parts. During
the downward movement of the upper link
member 35, the shoulder or block 46, en-
counters the detent 29 and swings it back
125 thereby releasing the setting arm. After the
truck wheels have passed the lever 27 the
spring 42^a returns the arm 42, the pawl 56
thereupon advancing the ratchet wheel 53
one tooth and turning the hands one step. 130

After leaving the lever 27 the truck wheels depress the second release lever 28 thereby positively retracting the detent 29 and positively releasing the setting arm 33 permitting the spring 45 and lever 44 to swing the upper link member 35 out of engagement with the lower link member 36.

An empty truck passing over the platform in the opposite direction, depresses lever 28, thereby preventing connection between the link members 35, 36. The truck then depresses lever 27 lowering the lower link member 36 without affecting the upper link member 35. It then depresses lever 26, setting the setting arm 33 and upper link member and then depresses lever 25, releasing said setting arm and upper link member.

Shortly before the predetermined number of truckloads have passed over the platform, the pin 77 comes into engagement with the trigger 78, and moves it forward against the detent 73, moving it into contact with the contact member 92, closing the bell circuit. Movement of the pin 77 one or more steps, disconnects detent 73 from the rod 71, which is thereupon pulled down by the spring 75; the hook 84 is thereby released from the latch 69 and the latter swung down, thereby releasing the barrier, which is swung forward by the spring 68^a. When the bell commences to ring, the truckers are warned, that nearly all of the predetermined number of loads have been counted. The bell ceases to ring when the last load has passed. The barrier is reset as has been explained, and the hands 51, 52 set for any predetermined number of truck loads within the limits of the capacity of the register. To prevent tampering with the setting hands, an electric contact member 97 is placed behind the shaft 54 with which said shaft contacts when depressed, said shaft and contact member 97 are in circuit with the bell which is caused to ring when the hands are being set.

It is to be observed, that the register cannot be actuated unless the levers are depressed in succession and that no strain is placed on the mechanism by the passage of the trucks over the primary levers. The parts are simple and not liable to get out of order, and very little adjustment and care is required to keep them in perfect working order.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new and desire to secure by Letters Patent:—

1. In a tallying machine, the combination of a platform, primary, compressible levers

therein, connectible and disconnectible register actuating mechanism, operatively connected to one of said levers, setting means operated by one of said levers for coupling said register actuating mechanism, means for holding said setting means in operative position, mechanism operated by another of said levers for releasing said setting mechanism, and means for uncoupling said register actuating mechanism.

2. In a tallying machine, the combination of a platform, primary, compressible levers therein, register actuating mechanism operatively connected with one of said levers, and having two members, normally disconnected from each other, setting means, operatively connected to another of said levers, for connecting said two members when said other lever is depressed, means for holding said setting means in operative position, mechanism operated by another of said levers for releasing said setting mechanism, and means for disconnecting said members.

3. In a tallying machine, the combination of a platform, primary levers therein, actuated by the passage of loads thereover, register actuating mechanism operatively connected to one of said levers, and having two members normally disconnected from each other, setting means operatively connected with another of said levers for operatively connecting said members, a detent for positively holding said setting means in operative position, a primary lever operated device for releasing said setting means from said detent, and means for disconnecting said members of the register actuating means.

4. In a tallying machine, the combination of a platform, primary levers therin, actuated by the passage of loads thereover, register actuating mechanism, operated by one of said levers, and having two members normally held disconnected from each other, setting means operatively connected with another of said levers for operatively connecting said members, a spring actuated detent for holding said setting means in operative position, and lever operated means operated by another platform lever for retracting said detent from its engagement with said setting means.

5. In a tallying machine, the combination of a platform, primary levers therein, actuated by the passage of loads thereover, register actuating mechanism, operated by one of said levers, and having two members normally held disconnected from each other, setting means operatively connected with another of said levers for operatively connecting said members, a spring actuated detent for holding said setting means in operative position, and lever operated means for retracting said detent from its engagement with said setting means, operated by two pri-

mary levers, the levers for the setting means and register actuating means being located between the detent actuating primary levers.

6. In a tallying machine, the combination 5 of a platform, primary levers therein, two link members, one for operating a register and one operatively connected with one of said primary levers, said link members being connectible and disconnectible, means 10 for normally holding said link members in disconnected position, a setting arm, operatively connected to one of said primary levers, for setting said link members in connected position, a detent arranged to hold 15 said setting means in operative position, holding the link members in connected position, and operative connections between said detent and another of said primary levers for positively disengaging said detent from 20 said setting means.

7. In a tallying machine, the combination 25 of a platform, primary levers therein, two link members, one for operating a register and one operatively connected with one of said primary levers, said link members being connectible and disconnectible, means 30 for normally holding said link members in disconnected position, a setting arm, operatively connected to another of said primary levers, for setting said link members in connected position, a detent arranged to hold 35 said setting means in operative position, holding the link members in connected position, and operative connections between said detent and two primary levers, said primary levers for the link members and setting arm being located between the detent actuating primary levers.

8. In a tallying machine, the combination 40 of a platform, primary levers therein, register actuating mechanism operatively connected with one of said levers, there being one member of said register actuating mechanism composed of two normally disconnected portions, setting means for said mem- 45

ber, operatively connected with another of said primary levers and releasable means for positively holding said setting means in set position.

9. In a tallying machine, the combination 50 of a platform, primary levers therein, register actuating mechanism operatively connected with one of said levers, there being one member of said register actuating mechanism composed of two normally disconnected portions, setting means for said member, operatively connected with another of said primary levers, means for returning said member into inactive position and releasable means for holding said setting 55 means in set position.

10. In a tallying machine, the combination 60 of a horizontally swinging spring actuated barrier, movable from an inactive position to an active position under the influence of the spring, a barrier holding latch, a latch retaining member for releasably holding said latch in engagement with said barrier, a connecting member for actuating said latch retaining member and trip mechanism for said connecting member, there being a lost motion connection between said connecting member and trip mechanism whereby said barrier may be restored to inactive position when said trip mechanism is 65 tripped condition.

11. In a tallying machine, the combination 70 of a register mechanism having an intermittently rotated element, an electric bell circuit, an electric switch in said circuit and a switch actuating member interposed between said switch and a member of said intermittently rotated element, a partial rotation of said member of the intermittently rotated element serving to close 75 the switch, and means for disengaging said switch actuating member from said member of the intermittently rotated element, substantially as and for the purpose set forth.

LINWOOD M. WHITEHEAD.
